UNITED STATES PATENT OFFICE.

JOHN EDGAR SIPPERLY, OF TROY, NEW YORK, ASSIGNOR TO UNITED SHIRT & COLLAR COMPANY, OF TROY, NEW YORK, A CORPORATION OF NEW YORK.

COLLAR.

1,314,986.

Specification of Letters Patent. Patented Sept. 2, 1919.

Application filed April 27, 1915. Serial No. 24,210.

To all whom it may concern:

Be it known that I, JOHN EDGAR SIPPERLY, a citizen of the United States, and resident of Troy, Rensselaer county, New York, have 5 invented certain new and useful Improvements in Collars, of which the following is a specification.

My invention relates to detachable shirt collars, used on shirts, shirt waists and the 10 like, and particularly to linen or cotton collars adapted to be starched in laundrying, and of folded or "turn-down" pattern. Its object is to produce a folded collar the "top" of which shall set snugly against the "band" 15 (except for the usual and necessary tie-space) for the central and major portion of its length, and stand away from the band at its ends, for a distance of approximately two or three inches, so as to produce the 20 effect of an ordinary folded collar at its back and sides and of a roll collar at its front.

In the drawings, which represent one 25 form of collar embodying my invention, Figure 1 is a perspective view of the collar in its worn position; Fig. 2 is a plan view of a blank from which the top of the collar is formed; Fig. 3 is a like view of the blank for a band.

30 11 designates the collar, comprising top 12 and band 13, it being understood that the band may be provided with the usual buttonholes 14. Band 13 is formed in the usual manner, its upper edge 15 being 35 curved in the ordinary form to fit the neck of the wearer. The invention lies in the top (as herein shown), the upper, attached edge 16 of which is cut to a curve corresponding to that of the upper edge of the band at 40 the central and major part of its length and at its ends departs from that curve, which is shown in Fig. 2 by dot and dash lines 17, by the addition of an integral, triangular gore or extra piece of fabric 18.

45 It is obvious that when the meeting edges 15 of band 13 and 16 of top 12 are stitched together in the usual manner, the band and top will lie flat and smooth at the central and major portions of their length, and will

show a rise or "pucker" at their ends, the 50 length of such pucker being defined by the length of gores 18. When the collar is starched and laundered, the top and band will set together in the usual fold at the back of the collar, while the effect of gores 55 18 will be to produce a tapering roll at the ends of the top 12, causing them to stand away from band 13, as shown in Fig. 1.

It is clear that the making of additional gores or triangles of fabric integral with 60 top 12 leaves the meeting seam of edges 15 and 16 hidden by top 12, as in the ordinary collar, and, for that reason, this is the preferred form of my invention. But it will be understood that certain changes may be 65 made in the device without departing therefrom.

It will be apparent that since the top edge of the finished collar is defined by the top edge of the band, which is of usual form, 70 the upper edge of the collar will be of usual contour, the gores in the top piece forming rolls.

What I claim is:

1. A folded "roll" collar comprising a band 75 of usual form and top, the meeting edges of which are parallel only in the intermediate portions of their length, the end portions of the top being increased in width below a line parallel to the corresponding upper 80 edge portions of the band, whereby the middle portions of the band and top, when laundered will be parallel while the end portions of the top will be spaced from the band in tapered rolls. 85

2. A folded "roll" collar comprising a band of usual form and top, the meeting edges of which are parallel only in the middle portions of their length, the end portions of the top being provided with triangular 90 gores having their widest portions at the ends of the top and their lower edges extending below a line parallel to the corresponding upper edge portions of the band for the purpose described. 95

3. A folded "roll" collar comprising a band of usual form and a top, the meeting edges of which are parallel to the edge of

the band throughout their intermediate and major portions, the end portions of the top being provided with gores, whereby the top is caused to depart at its ends from its parallel relation to the band, and whereby, when the edges of the band and of the top are secured together, they meet in a line of usual

collar contour, the top forming rolls at their ends.

JOHN EDGAR SIPPERLY.
